UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

OIL-WELL PACKER.

Application filed February 1, 1927. Serial No. 165,098.

My invention relates to packers for oil and gas wells, and particularly to that type of packers commercially known as hook wall packers. A packer of the character stated is 5 shown in United States Letters-Patent No. 1,009,328, granted to me November 21, 1911.

Among the objects of the present invention are: to provide in a packer construction of the type mentioned means whereby the 10 gripping portions of the slips when the packer is set will bear uniformly throughout their length against both the slip expanding means and the wall of the casing in which the packer is being set; to provide the slips with 15 very long neck portions; and to provide straight contact surfaces between the side edges of the necks of the slips and the neck receiving slots or openings of the cage, whereby sand and other substances will not 20 lodge therebetween and interfere with the desired movement of the slips.

In the accompanying drawing, which illustrates an application of my invention:

Fig. 1 is an elevational view of a portion 25 of a packer embodying my invention;

Fig. 2, a detail vertical sectional view, showing a portion of the packer and a casing wall particularly showing the position of the gripping portion of a slip relatively to the 30 wall before expansion;

Fig. 3, a view similar to Fig. 2, showing the position of a slip after expansion;

Fig. 4, a cross sectional view taken on line IV—IV of Fig. 1; and

Fig. 5, a cross sectional view taken on line V—V of Fig. 1.

As the present invention relates only to the cage and slip construction of hook wall packers, I have deemed it unnecessary to show a 40 complete packer of this type; for the parts of the packer not shown reference may be had to my Patent No. 1,009,328 hereinabove referred to.

My invention contemplates the employment 45 of a hollow body member 5 adapted to have its lower end connected with a tubing coupling member 6. It will be understood that the hollow body 5, in addition to coupling 6 and a slip expanding member or sleeve 7, carries at its upper end a coupling, and interposed between the upper coupling, and the expanding sleeve 7, a packing element.

As illustrated, 8 designates the slip-cage 55 designed to carry a plurality of slips 9, said

slips 9 being loosely connected with the cage so as to have a tilting movement to and from the conical sleeve 7. The slips 9 constitute an important and characteristic feature of the present invention, and, as shown, each includes a long neck or rein portion 10, said neck being made considerably longer than the necks of slips as heretofore constructed. The necks are formed with straight unbevelled vertically extending edges 11 to form, 60 for a portion of their lengths, flat contact faces adapted to contact with straight walls of neck receiving openings formed in the slip-cage.

Each slip is provided at one end, the upper 70 end, with a serrated or gripping portion 12 and at its lower end with outwardly extending lugs 13 for tiltingly engaging the lower end of the slip with the slip-cage. Each lug 13 is preferably formed with a beveled face 75 14 designed to cooperate with beveled walls of the slip-cage, as hereinafter described.

The long neck 10 of the slip is formed with outwardly extending flanges 15, thereby forming a groove or channel 16 for the reception of a spring member 17, said spring member 17 being secured at one end to the slip-cage by rivets, as shown at 18. The neck portion 10 is bent inwardly slightly as it approaches the serrated portion 12, as shown 85 at 19.

The slip-cage 8, as illustrated and as preferred, comprises an upper annular slotted portion 20 and a lower ring portion 21. The upper portion 20 is provided with a series 90 of openings or slots 22 designed to receive the several slip members or the neck portions 10 thereof. The vertically extending walls 23 of the openings 22 are formed straight or unbevelled to engage the unbevelled vertically 95 extending edges 11 of the neck 10. These straight contacting faces 23 and 11, when the parts are assembled, prevent sand and other foreign substances becoming lodged therebetween and interfering with the desired movement of the slips.

24 designates recesses formed in the slip-cage. These recesses are adapted to receive the lugs 13 of the neck portion 10. It will be noted that the vertically extending walls 105 of the said recesses are bevelled to correspond with the beveled faces 14 of the lugs. This will prevent the lugs from being forced outwardly through the said recesses. In order to permit the desired movement of the lugs 110

13 within the recesses, the recesses are of sufficient depth to allow for a slight vertical movement of the lugs therein.

The lower ring portion of the slip-cage is 5 provided with hooks 25 for engagement with a pin or member 26 carried by the body 5. This last mentioned construction is similar to the construction shown in my Patent No. 1,009,327 aforesaid.

10 The position of the hooks and the pin or lug 26 shown by Fig. 1 are such as to maintain the slips in inoperative position. In order that the slips may be expanded against the casing, the lug or pin 26 must be free of the 15 hooks 25; this is accomplished by rotation of the tubing to which the packer is attached and in turn by the rotation of the hollow body 5.

By the provision of the long neck portion 10, I provide a construction that will permit 20 the desired contact of the serrated portion between the expanding member and the casing, when the packer is set, throughout the length of the serrated portion, that is impossible where the neck portion is short as in constructions heretofore made. The length of the neck portion 10 should be such as to permit of 25 adjustment between the parts for the purpose stated.

It will be noted with a long neck, as shown, 30 the angularity at the pivoting point between the cage and the lower end of the neck is considerably less than with a short neck, therefore, a full contact of the serrated portion between the expanding means and the 35 casing is assured. A reference to Figs. 2 and 3, shows the position of the serrated portions of the slips before and after expansion.

Figs. 3 shows the serrated portion after it

has been forced outwardly by the sleeve, and it will be noted that it is in close contact with 40 the casing throughout the length or depth of the serrated portion, and that the face opposite the serrated portion is backed up in close engagement with the expanding member 7.

What I claim is:

1. In an oil well packer, a slip-cage, a slip having a loose connection with the cage, said slip characterized by having a long neck portion whereby the angularity between the cage and the neck is small upon expansion of the 50 slip, said neck being formed with straight un-beveled edges, said cage having a neck receiving opening therein having straight walls for engaging the straight edges of the neck portion of the slip.

2. In an oil well packer, a slip-cage, a slip carrier by and movable relatively to the cage and having a long neck portion formed with straight edges and a lug on its lower end, said lug having an outer tapered face, said cage having a neck receiving opening having straight walls for engaging the straight edges of the neck portion, and a lug receiving recess having a wall thereof beveled to engage 60 the tapered face of the lug.

3. In an oil well packer, a slip-cage, a slip carried by the cage having a serrated gripping portion and a long, relatively rigid neck extending from the gripping portion, said neck adjacent the gripping portion being formed with a bend and with straight contact edges, said cage having a neck receiving opening having straight walls for engaging the 70 straight edges of the neck.

In testimony whereof I affix my signature.

PATRICK H. MACK.
